UNITED STATES PATENT OFFICE

THOMAS H. PARKER, OF SAN FRANCISCO, CALIFORNIA.

CENTRIFUGAL SEPARATOR.

1,262,384.

Specification of Letters Patent.

Patented Apr. 9, 1918.

Application filed May 23, 1917. Serial No. 171,254.

To all whom it may concern:

Be it known that I, THOMAS H. PARKER, a citizen of the United States, residing at the city and county of San Francisco and State of California, have invented new and useful Improvement in Centrifugal Separators, of which the following is a specification.

This invention relates to centrifugal separators of the type shown and described in my Patent No. 1,212,996, dated January 16th, 1917.

This type of separator comprises a rotatable distributor carried on a vertical axis and arranged to discharge the material to be separated radially therefrom and a rotatable concave shell surrounding the distributor and spaced therefrom to receive the material from the distributor, said shell having open-ended sides projecting above and below the distributor and capable, in operation, of separating the light from the heavy particles and discharging the light particles over the top edge and the heavy particles below.

The invention in my prior patent is shown embodied in a de-watering device for metallurgical pulp and like separators; and the present invention has for its object to so modify the structure as to suit it especially for the separation of cream, oil and like liquids.

To adapt the device to the separation of cream from milk, oil from water, etc., in a satisfactory manner certain structural changes are necessary in order that a seal of heavy liquid particles, such as milk or water, may be maintained between the distributor and the surrounding concave shell, so that the lighter liquid particles, such as cream or oil, cannot pass below the distributor and out at the bottom of the shell. These changes include the provision of retaining lips at the top and bottom of the concave shell and the shaping of the shell so that a considerable mass of heavy liquid particles may be held in place therein under normal operation, also the provision on the distributor of horizontally projecting, disk-like members directed toward the center of the concave shell and extending within the mass or film of heavy liquid particles present within the shell. The lighter liquid particles cannot, therefore, pass below the distributor and are consequently discharged over the top of the shell. Other improve-

ments include the provision of means for feeding the material to the distributing disk from a tank below, an overhead drive for the distributing disk, and the connecting of the surrounding shell to the distributor so that said shell is carried directly by and rotated with said distributor.

In the accompanying drawing:

The figure shows a vertical, central, sectional view of a device embodying my invention.

Referring now in detail to the accompanying drawing, the device there shown comprises a frame 10, at the top of which is journaled a drive shaft 11, detachably connected to which is a hub 12 carrying, by means of radial webs 13, a funnel-shaped distributor 14, the flared ends 15 of which are disposed at the top and extend horizontally somewhat in the shape of a disk. Surrounding and connected to the ends 15, by means of webs or spiders 16, is an annular, concaved shell 17, the concavity in which is substantially V-shaped in cross section and the sides of which extend equally above and below the ends 15 of the distributor. The top and bottom of the shell 17 are open and the marginal edges are provided with retaining lips 18 projecting inwardly.

The funnel-shaped distributor has a tubular extension 19 projecting below into a tank 20 containing the material to be separated. This tubular extension is fitted internally with spiral or inclined vanes 21 which, when the parts are rotated, force the material upwardly and into the distributor. Surrounding the upper end of the shell 17 is a horizontal ledge 22 over which the light liquid particles discharge past to a launder 23 covered by a hood 24. Below the shell 17 and surrounding the same is a launder 25 for the heavy liquid particles discharged.

In operation, the hub 12 is driven at sufficiently high speed to cause the vanes 21 to feed the material upwardly to the distributor and the latter to discharge the same radially outward against the concaved shell. The first effect will be for the material to fill the concavity in the shell and, owing to the shape of the latter, a sufficient mass of liquid particles will be retained therein normally to immerse the edges of the disk-like member 15 and seal the space between the said disk and shell. Centrifugal force will move the heavier particles outwardly against the walls of the shell while the lighter par-

ticles will remain toward the inside, and as the feed of material continues the lighter particles will be forced upwardly over the rim of the shell, while the heavier particles 5 will pass out at the bottom of the shell.

None of the light liquid particles can escape below the distributor on account of the seal formed by the mass of heavy liquid particles between the rim of the disk and the 10 shell and at the same time the heavy particles cannot escape above on account of the retaining lips 18. The pressure of the lighter particles against the heavier aided by gravity will insure the discharge of the 15 heavy particles at the bottom of the shell.

The upper rim of the shell has its inner circumferential face 26 made flat and inclined inwardly and downwardly so that after the light particles pass the lip they are 20 still retained in place. The centrifugal forces applied thereto at this point will continue the separation, and, therefore, any heavy particles escaping past the lip will not be discharged with the light material.

Various changes in the construction and arrangement of the several parts herein shown and described may be made without departing from the spirit of my invention as disclosed in the appended claims.

Having thus described my invention, what I claim and desire to secure by Letters Patent is—

1. In a centrifugal separator for liquid material, a rotatable distributor carried on a vertical axis and discharging the material radially outward, a rotatable, concave shell surrounding the distributor and receiving the material to be separated therefrom, said shell having open-ended sides projecting above and below the distributor and capable 35 in operation of discharging the light particles over the top edge and the heavy particles below, and inwardly projecting lips on the ends of the shell, said lips being so disposed as to confine a mass of heavy particles normally within the curvature of the shell both above and below the rim of the distributor and sufficient in thickness to immerse the latter, whereby incoming light 40 particles are prevented from passing below the rim of the distributor and act in conjunction with incoming heavy particles and the weight of the confined mass to force the heavy particles adjacent to the lower end of 45 the shell over the bottom retaining lip.

2. In a centrifugal separator for liquid material, a rotatable distributor carried on a vertical axis and discharging the material radially outward, a rotatable, concave shell 50 surrounding the distributor and receiving the material to be separated therefrom, said shell having open-ended sides projecting above and below the distributor and capable in operation of discharging the light particles over the top edge and the heavy par-

ticles below, said shell having its sides substantially V-shaped in cross section extending above and below the distributor equal distances and at the same angularity, and inwardly projecting retaining lips on the 70 ends of the shell to retain a mass of heavy particles in place between the distributor and shell sufficient in thickness to immerse the rim of the distributor and thereby prevent the escape of light particles below the 75 distributor.

3. In a centrifugal separator for liquid material, a rotatable distributor carried on a vertical axis and discharging the material radially outward, a rotatable, concave shell 80 surrounding the distributor and receiving the material to be separated therefrom, said shell having open-ended sides projecting above and below the distributor and capable in operation of discharging the light liquid 85 particles over the top edge and the heavy liquid particles below, and means connected to and rotatable with the distributor to lift the material from below and feed it to the distributor.

4. In a centrifugal separator for liquid material, a rotatable distributor carried on a vertical axis and discharging the material radially outward, a rotatable, concave shell 90 surrounding the distributor and receiving the material to be separated therefrom, said shell having open-ended sides projecting above and below the distributor and capable in operation of discharging the light liquid 95 particles over the top edge and the heavy liquid particles below, and means connected to and rotatable with the distributor to lift the material from below and feed it to the distributor, said means comprising a tubular extension fitted internally with inclined 100 vanes.

5. In a centrifugal separator for liquid material, a rotatable distributor carried on a vertical axis and discharging the material radially outward, and a rotatable, concave 110 shell surrounding the distributor and receiving the material to be separated therefrom, said shell having open-ended sides projecting above and below the distributor and capable in operation of discharging the light 115 liquid particles over the top edge and the heavy liquid particles below, said distributor being in the shape of an inverted bell and having a flat, horizontally disposed discharge end and means for supplying material to said distributor from below.

6. In a centrifugal separator for liquid material, a rotatable distributor carried on a vertical axis and discharging the material radially outward, a rotatable, concave shell 125 surrounding the distributor and receiving the material to be separated therefrom, said shell having open-ended sides projecting above and below the distributor and capable in operation of discharging the light liquid 130

particles over the top edge and the heavy liquid particles below, an overhead bearing from which the distributer is suspended and driving means for the distributer comprising a hub connected by radial webs to the distributer and rotatable driving connections at the upper end thereof.

In testimony whereof I have hereunto set my hand in the presence of two subscribing witnesses.

THOMAS H. PARKER.
